[57] CLAIM

The ornamental design for a marine life display unit, as shown and described.

DESCRIPTION

FIG. 1 is a perspective view of a marine life display unit showing my new design;

FIG. 2 is a front view thereof;

FIG. 3 is a rear view thereof;

FIG. 4 is a side view thereof, the other side view being substantially the same;

FIG. 5 is a top view thereof;

FIG. 6 is a bottom view thereof; and,

FIG. 7 is an additional perspective view thereof, illustrating a display light located within the top hood of the unit.

FIG. 1

FIG. 4

FIG. 2

FIG. 3

FIG. 5

FIG. 6

FIG. 7
